TRAIN CONTROL SYSTEM

Frank H. Nicholson, Penn Township, Allegheny County, Pa., assignor to The Union Switch & Signal Company, Swissvale, Pa., a corporation of Pennsylvania

Application July 8, 1938, Serial No. 218,137

6 Claims. (Cl. 246—63)

My invention relates to train control systems, and particularly to systems of the type incorporating receiving apparatus usually located on a train and capable of operation either over territory in which the wayside is supplied with coded current or over territory in which the wayside is supplied with non-coded current.

More particularly my present invention relates to systems in which the receiving apparatus is capable of selectively responding to alternating current flowing in the track rails and periodically varied at different rates according to traffic conditions. A system of this general type is disclosed in United States Patent No. 1,986,679 granted to Lloyd V. Lewis on January 1, 1935.

My present invention is an improvement over that shown in Patent No. 1,909,709, granted to me on May 16, 1933, and contemplates train carried apparatus capable of operation not only upon the coded wayside current of the type disclosed in the Lewis patent identified above, and which may, for example, be of a frequency of 100 cycles per second, but also in response to the continuous flow of uncoded current of a different frequency such as 140 cycles per second flowing in the track rails. For this purpose a modulator is provided for periodically varying the current supplied by a receiver energized from the wayside.

An important feature of the present invention is the provision in a train control system of the type disclosed in my previous Patent No. 1,909,709 of means on the train effective when the system is to be operated in response to non-coded current for causing the train carried modulator to periodically tune and detune (at the frequency of the non-coded wayside current) the circuit through which energy from the receiver is supplied to the train carried traffic control device. In a system of this type the traffic control device on the train is rendered immune to false operations by random current produced in the receiver by stray magnetic fields, shock excitation, or other causes.

I shall describe one form of train control system embodying my invention, and shall then point out the novel features thereof in claims.

The accompanying drawing is a diagrammatic view showing one form of apparatus embodying my invention.

This drawing discloses as much of a train control system as is necessary to an understanding of my invention and includes a train control receiver R of the usual form suitable for picking up current from the track rails. Energy induced in the receiver R is supplied, through a

receiver circuit including condenser 1 , with a filter designated generally by the reference character F . The filter F is connected with a train carried traffic control device, here shown as an electron tube $E1$ which is coupled by a transformer $T2$ to a second electron tube $E2$. The output circuit of tube $E2$ controls, by way of a transformer $T3$, the winding of a master relay MR which may control train carried governing means in any well known manner such, for example, as shown in the Lewis Patent No. 1,986,679 identified above.

In the form here shown, the filter F comprises an auto transformer $T1$ connected with the receiver circuit and having its secondary terminals connected across the grid and filament of the train control device $E1$. A condenser 3 is permanently connected across the auto transformer $T1$ and tunes the filter to resonance at the frequency of the non-coded current with which the system is intended to operate. The condenser 1 in the receiver circuit also tunes that circuit to resonance at the same frequency.

The train carried apparatus also includes a manually operable cutover switch S comprising two contacts 4 and 5 closed in the position illustrated which corresponds to operation of the equipment over coded territory. When contact 4 of switch S is closed a condenser 6 is connected in parallel with condenser 3 in the filter F for tuning the filter to resonance at the frequency of the coded current. Similarly when contact 5 of switch S is closed a condenser 7 is connected in parallel with condenser 1 to tune the receiver circuit to the frequency of the coded current.

With the switch S in the position shown, if the receiver is located in inductive relation with track rails supplied with coded current, the energy induced in the receiver passes through the receiving circuit and the filter F to control the device $E1$ and hence the master relay MR .

It is desired however that the system shall also respond when the receiver is in inductive relation with conductors carrying non-coded current. For this purpose the train is provided with a modulator M which may be of the construction disclosed in United States Patent No. 1,858,876, issued May 17, 1932, to P. N. Bossart, and comprises a winding 8 which when energized moves an armature in one direction thereby breaking the operating circuit at contact 9 , whereupon a spring restores the armature to again complete the operating circuit at contact 9 . Modulator M therefore operates to periodically open and close contacts 10 and 11 , and the parts are so designed

that this takes place at the frequency of the code interruptions in the code current which it is desired to impose upon the non-coded current for operation of the traffic control device on the 5 train.

5 I have provided a condenser 12 which is connected across condenser 3 of the filter F when contact 10 of the modulator is closed, and I have provided another condenser 13 which is connected across condenser 1 of the receiving circuit when contact 11 of the modulator is closed. Furthermore I have provided an energizing circuit for the modulator M including contact 14 of switch S and a suitable source of energy such 10 as a generator G. It is apparent therefore that when the switch S is moved to the position to open contacts 4 and 5, contact 13 will become closed to actuate modulator M.

In operation the switch S will be moved to 20 the position illustrated in the drawing when it is intended that the system shall be used in territory supplied with coded wayside current. Under these circumstances, both the receiver circuit (condensers 1 and 7) and the filter (condensers 3 and 6) are tuned to resonance at the frequency of the coded current.

If now it is intended that the system should operate in territory where the wayside is supplied with non-coded current the switch S is 25 moved to the dotted line position thereby rupturing the circuits for condensers 6 and 7 and causing the receiving circuit and the filter to be tuned to resonance at the frequency of the non-coded current. At the same time the closing of contact 13 of switch S actuates the modulator M and the contacts 10 and 11 of the modulator then operate at the code frequency which is to be simulated in the train carried apparatus to alternately connect condensers 12 and 13 in the filter 30 and receiving circuits, respectively, for the purpose of detuning those circuits for the non-coded frequency. The effect of this operation is to periodically vary the impedance offered by the receiving circuit and the filter to the flow of current from the receiver to the device E1, thereby causing in the current actually supplied to E1 periodic variations at the rate of operation of modulator M and these period variations in the current supplied to E1 cause that device to respond and hence to control through the master 35 relay MR and associated apparatus the train carried equipment in exactly the same way as if the receiver were supplied with coded current.

Experience has shown that when the receiver 40 is operating in non-coded territory there may be false currents in the receiver. These false currents may result from the stray field produced by magnetized wheels or from shock excitation due to periodic striking of the receiver by a loose 45 object on the locomotive. It is important that these false currents shall not falsely operate the train carried apparatus. With the apparatus embodying my invention this is prevented because, since the train carried modulator M merely changes the tuning of the receiver circuit and the filter, any false current in the receiver due to the causes suggested above will merely be changed in frequency by the operation of the modulator and will not be substantially changed 50 in amount. The false current will therefore continue to energize device E1 and the magnitude of the false current will not be periodically varied as is necessary in order to cause operation of the master relay MR in accordance with the coded 55 current.

Even under the worst condition, therefore, that is, when shock excitation becomes so frequent that the false currents in receiver R are practically continuous, the operation of the modulator M will merely change the frequency of the 5 false currents supplied to device E1 and will not materially change the magnitude of this current so that the train carried apparatus is not falsely actuated. When the receiver R is energized by the non-coded current, however, the effect of the 10 modulator is to periodically tune and detune the filter and receiving circuits at this particular frequency and this results in periodic and substantial variations in the magnitude of the current supplied to the device E1 which causes a 15 consequent operation of the master relay MR.

It will be understood that if the false output from the receiver is of an intermittent character, the master relay may operate at the frequency of the intermittent excitation of the receiver. 20 Tests have shown however that when this intermittent excitation approaches the periodicity of the code customarily employed for a clear indication (180 per minute) the output of the receiver-filter combination becomes substantially 25 continuous and the master relay remains at rest.

It will be apparent from the foregoing that I have devised a system of train control capable of operation over either coded or non-coded territory and immune to false operation from shock 30 excitation of the receiver.

Although I have herein shown and described only one form of train control system embodying my invention, it is understood that various changes and modifications may be made therein 35 within the scope of the appended claims without departing from the spirit and scope of my invention.

Having thus described my invention, what I 40 claim is:

1. In a train control system including a receiver to be energized by modified or unmodified current flowing in a wayside conductor, a traffic control device responsive to the influence of modified current, circuit means for connecting said receiver with said device, a modulator, and means controlled by said modulator for tuning said circuit means alternately and repeatedly to two different frequencies for so modifying the current supplied to said device by the receiver when the latter is energized by unmodified current as to cause response of said device.

2. In a train control system including a receiver to be energized by modified current of one frequency or unmodified current of a second frequency flowing in a wayside conductor, a traffic control device responsive to the influence of modified current, a filter connected with said device and tuned to resonance at said second frequency, a receiver circuit connecting said receiver with said filter and tuned to resonance at said second frequency, a modulator effective when actuated to periodically detune said filter and said receiver circuit for said second frequency, a switch, means controlled by said switch in one position to change the tuning of said filter and receiver circuits to resonance at said one frequency, and means controlled by said switch in a different position to actuate said modulator.

3. In a train control system including a receiver to be energized by unmodified current, a traffic control device responsive to the influence of periodically varied current, circuit means for connecting said receiver with said device, and a modulator for periodically and alternately tuning

and detuning said circuit means for the frequency of said unmodified current for causing operation of said device in response to said unmodified current in said receiver but for rendering said device immune to the effects of shock and stray field excitation of said receiver.

4. In a train control system including a receiver to be energized by non-coded periodic current, a traffic control device responsive to the influence of coded current, circuit means for connecting said receiver with said device, and a modulator for tuning said circuit means alternately and repeatedly to two different frequencies to code the current supplied to said device from 10 said receiver.

5. In a train control system including a receiver to be energized by non-coded periodic current, a traffic control device responsive to the influence of coded current, circuit means for connecting said receiver with said device, and a 15

20

modulator for coding the current supplied to said device from said receiver and operating to tune said circuit means alternately and repeatedly to two different frequencies one of which corresponds to the periodicity of said non-coded current. 5

6. In a train control system including a receiver to be energized by coded alternating current of a first frequency or non-coded alternating current of a second frequency, a traffic control device responsive to said coded current, circuit means for connecting said receiver with said device, and a modulator for alternately and repeatedly tuning said circuit means to resonance at said first and said second frequencies to code the current supplied to said device from said receiver when the latter is energized by non-coded current. 10 15
